UNITED STATES PATENT OFFICE.

ALFRED J. MANNING, OF IRVINGTON, NEW YORK, ASSIGNOR TO THE YALE & TOWNE MANUFACTURING COMPANY, OF STAMFORD, CONNECTICUT.

DESIGN FOR A BAR-HANDLE.

SPECIFICATION forming part of Design No. 16,244, dated September 8, 1885.

Application filed June 8, 1885. Term of patent 7 years.

To all whom it may concern:

Be it known that I, ALFRED J. MANNING, a citizen of the United States, residing at Irvington, in the county of Westchester and State of New York, have invented and produced a new and original Design for a Bar-Handle, of which the following is a specification, reference being had to the accompanying drawings, forming a part thereof.

In the drawings, Figure 1 is a plan view of my design for a bar-handle, and Fig. 2 a side view.

My design consists, essentially, of a flat piece, A, to which is attached a bar, B, curved inwardly under the bar like a volute coil or scroll at each end, as shown at C. A concaved or curved cap, E, is also shown, starting from the outside of the bar and curving inward from the bar to the flat plate A.

This may be used at either or both ends, or 20 may be dispensed with.

What I claim as my design for a bar-handle, and desire to secure by Letters Patent, is—

1. A design for a bar-handle, consisting of plate A and bar B, curved inwardly at each 25 end under the bar like a volute coil, as shown and described.

2. A design for a bar-handle, consisting of plate A and bar B, curved inwardly at each end under the bar like a volute coil, and provided with one or more caps, E, as shown and 30 described.

In testimony whereof I have hereunto subscribed my name.

ALFRED J. MANNING.
